CONRAD WERRA, OF WAUKESHA, WISCONSIN, ASSIGNOR TO WERRA ALUMINUM FOUNDRY COMPANY, OF WAUKESHA, WISCONSIN, A CORPORATION OF WISCONSIN.

VACUUM MOLDING-MACHINE.

1,180,352.

Specification of Letters Patent. Patented Apr. 25, 1916.

Application filed June 1, 1914. Serial No. 841,993.

To all whom it may concern:

Be it known that I, CONRAD WERRA, a citizen of the United States, and resident of Waukesha, in the county of Waukesha and State of Wisconsin, have invented new and useful Improvements in Vacuum Mold- 5 ing-Machines, of which the following is a description, reference being had to the accompanying drawings, which are a part of this specification.

This invention relates to improvements in vacuum molding machines of that type more particularly adapted for molding household utensils.

It is one of the objects of the present invention to provide a vacuum molding machine in which metal utensils of various kinds having very thin walls may be easily molded in a very simple manner.

A further object of the invention is, to provide a vacuum molding machine having means for melting and keeping a supply of molten metal for directly supplying the molding dies with metal as soon as the completed utensils are removed from the dies to form substantially a continuous operation.

A further object of the invention is to provide a vacuum molding machine in which pneumatic means is utilized for moving one of the molding members to molding position, and also to cause the molten material to flow into the molding space of the dies.

A further object of the invention is, to provide a vacuum molding machine in which the flow of molten metal to the mold may be easily controlled during the molding operation.

A further object of the invention is to provide a vacuum molding machine in which means are provided for automatically stripping the completed utensil from the die members.

A further object of the invention is to provide a vacuum molding machine particularly adapted for making aluminum castings, which is of simple construction, is strong and durable, and is well adapted for the purpose described.

With the above and other objects in view, the invention consists of the improved vacuum molding machine and its parts and combinations as set forth in the claims, and all equivalents thereof.

In the accompanying drawing in which the same reference characters indicate the

same parts in all of the views: Figure 1 is a central vertical sectional view of the improved vacuum molding machine; and Fig. 2 is an inverted detail view of a portion of the upper die member.

Referring to the drawing the numeral 5 indicates a frame consisting of the base member 6, standards 7 projecting upwardly therefrom, and a top member 8 supported on the upper ends of the standards. A 65 burner chamber 9 mounted on the top member 8 is of circular shape in cross section and is formed of an outer metal casing 10 lined with fire brick 11 and having a burner inlet opening 12 extending through the side 70 wall thereof to receive the burner 13. The diametrically opposite side wall of the burner chamber is provided with an air inlet opening 14 to supply air for combustion and also to serve as a peep opening to view 75 the melting pot 15 positioned within the fire chamber and resting on and bolted to the top plate 8. This melting pot is of conical form with its smaller or discharge end 16 extending downwardly and having an 80 annular flange 17 through which the securing bolts 18 pass to fasten the melting pot to the top member 8.

The upper open end of the burner chamber is covered by a top plate 19 having a 85 medial opening 20 of approximately the same diameter as the upper end of the fire pot and also having a series of burnt gas outlet openings 21 which are in register with the annular span 22 formed between the 90 melting pot and the burner chamber, to permit the escape of the products of combustion from said chamber. The portion of the top plate covering the annular space 22 is protected by fire brick 23 or other heat resist- 95 ing material, and is provided with openings 24 which register with the openings 21 of the plate.

A guide member 25 bolted to the top plate and extending upwardly and diametrically 100 across the plate above the melting pot is provided with a vertically extending bored guide portion 26 to slidably receive the stem 27 of the valve 28.

The valve is of tapered form and enters 105 the valve seat forming the discharge opening 29 of the melting pot. A lever 30 pivotally connected at its inner end to the upper end of the valve stem and having a linked connection 31 with the guide member 25, 110

serves to control the movement of the valve and the discharge of molten metal from the melting pot.

- The die member for receiving the molten material is positioned below the burner chamber and comprises the fixed die section 31 secured to the top member 8 by the bolts 18 and the movable die section 32 which is mounted on the upper end of the piston, 10 plunger 33 extending upwardly from the cylinder 34. The cylinder 34 is mounted on the base member 6 and the piston plunger 33 extends slidably through the upper open end thereof and is reciprocated by 15 means of compressed air, supplied through the pipe 35 from a source of supply 34'. The compressed air from the air pump or source of supply is controlled by means of a three way valve 35' connected to the pipe, which 20 may be turned in one direction to admit the air to the cylinder to force the piston upwardly, or turned in another direction, to exhaust the air from the cylinder and permit the piston to drop by gravity.
- 25 The fixed die section 31 is provided with an annular flange 36 which coacts with a similar flange 37 carried by the movable die section to form a sealed joint between the two sections when they are in closed position to receive the molten metal. The adjacent face portions of the flanges are provided with annular grooves 38 and 38' and a packing ring 39 formed of asbestos or other desirable material is positioned in 30 the groove 38' and is adapted to enter the groove 38 of the upper flange, and seal the joint when the two sections are in closed position. The upper or fixed flange 36 and the edge portion of the upper die section 35 are also provided with annular grooves 40 which are connected together, and to the molding space 41 of the upper section, by radial grooves 42. These last mentioned grooves are provided to permit the air to be 45 exhausted and a vacuum created in the molding space 41 by means of the vacuum pump 43 which is connected by a pipe 44 to the upper flange at a point above the outer groove of the flange 36.
- 50 The upper portion of the die 31 is provided with an inlet opening 45 which is in register with the valve opening 29 of the melting pot.
- The movable die section is provided with 55 spring actuated stripper rods 46 slidably mounted in the die member 32 and plunger 33 and which are adapted to engage the edge portion of utensils molded or cast in the die, and strip it from the male portion 60 47 of the die while the said male portion is moving downwardly and out of engagement with the fixed die section.

While the die shown is adapted for a simple household utensil it is to be understood that other forms of dies may be used

for making various kinds and shapes of utensils without departing from the spirit and scope of the invention.

In use the aluminum is reduced to a molten mass by the burner, and the movable die section is forced upwardly into engagement with the fixed die by admitting air under pressure to the cylinder. When thus positioned the air is exhausted from the molding space between the two die sections, 70 and the valve in the melting pot is opened to permit the molten metal to flow into the space formed between the die sections. As a partial vacuum is formed in the molding space the molten material will be caused to 80 completely fill the entire space and form a perfect casting without the liability of having blow holes therein. When the cast metal in the die has cooled sufficiently to maintain its shape, the valve controlling the compressed air pipe is turned to exhaust the compressed air in the cylinder and the piston will withdraw the movable die section from the fixed section, and while moving downwardly the stripper rods under the action of 85 the springs move upwardly to strip the cast utensil from the movable die section and leave the said utensil in the upper fixed die. In further cooling, the utensil will contract and finally drop out of the fixed die, and the 90 operation of casting may then be repeated.

From the foregoing description it will be seen that the vacuum molding machine is of simple construction and is well adapted for the purpose described.

What I claim as my invention is:

1. In a vacuum molding machine, the combination, with a frame, a burner chamber mounted thereon, a melting pot disposed within the burner chamber and having a discharge opening at its lower end, and a valve member controlling said discharge opening, of a die member secured to the frame beneath the melting pot and having an opening therein communicating with said discharge opening, and a die member reciprocally mounted upon the frame and movable into engagement with the fixed die to form a casting space therebetween, means carried by the die members for forming an air-tight joint between said members, and means for exhausting the air from the casting space of the die.

2. In a vacuum molding machine, the combination, with a frame, a burner chamber mounted thereon, a melting pot disposed within the burner chamber and having a discharge opening at its lower end, and a valve member controlling said discharge opening, of a die member secured to the frame beneath the melting pot and having an opening therein communicating with said discharge opening, a support movably mounted upon the frame, a die member carried by said support, means for vertically 120

reciprocating said movable support and die to bring said die members together to form a casting space therebetween, means carried by the die members for sealing them together to form an air-tight joint between the same, and means for exhausting the air from the casting space of the die.

3. In a vacuum molding machine, the combination, with a frame, a burner chamber mounted thereon, a melting pot disposed within the burner chamber and having a discharge opening at its lower end, and a valve member controlling said discharge opening, of a die member secured to the frame beneath the melting pot and having an opening therein communicating with said discharge opening, a die member vertically movable with respect to the frame and said fixed die to form a casting space between said members, sealing flanges carried by each of said die members to form an air-tight closure between the dies when they are brought together, and means for exhausting the air from the casting space of the die members.

4. In a vacuum molding machine, the combination of a frame, a fixed die member mounted thereon, a die member movably mounted in the frame and movable to a position adjacent the fixed die member to form a casting space therebetween, means for conducting metal to the casting space, means carried by the die members for sealing them together to form an air-tight joint between the same, means for exhausting the air from the casting space, and stripper rods automatically operable to move the cast article from the movable die member when said die member is moved away from the fixed die member.

5. A vacuum molding machine, comprising a two part die member comprising fixed and movable die members having a casting space therebetween, a burner chamber positioned above the die member, a melting pot extending into the burner chamber for supplying material in a molten state to the casting space of the casting, means controlling the flow of material from the melting pot to the die space, means for exhausting the air from the die space preparatory to supplying the molten material thereto, a cylinder positioned below the two part die, a piston slidably extending into the cylinder and connected to the movable die member of the two part die, and means for supplying a fluid under pressure to the cylinder.

6. A vacuum molding machine, comprising a two part die member having a casting space therebetween, a burner chamber positioned above the die member, a melting pot extending into the burner chamber and having a discharge opening communicating with the casting space of the two part die, a valve member controlling said discharge

opening, means for sealing the joint of the die parts, means for exhausting the air from the casting space of the die member, a cylinder positioned below the die member, a piston slidably extending into the cylinder and connected at its upper end to one part of the two part die, and means for supplying a fluid under pressure to the cylinder.

7. A vacuum molding machine, comprising a base member, having a cylinder provided with a piston, a burner chamber mounted on supports extending upwardly from the base member, a melting pot extending into the burner chamber and having a discharge opening in its lower portion, a valve member controlling the flow of material through said opening, an upper die section member connected to the lower portion of the burner chamber and having a recessed portion into which the discharge opening of the melting pot opens, said die member having an annular flange provided with an annular groove in communication with the recessed portion of the die, a lower die section member mounted on and movable with the piston and arranged to engage the upper die section member to form a casting space therebetween, said lower die section member having an annular flange provided with an annular recess which registers with the annular recess of the upper annular flange, a sealing packing positioned in one of the annular recesses and entering the other annular recess to seal the casting space between the two die sections, means for exhausting the air in the sealed casting space, and means for supplying a fluid under pressure to the cylinder.

8. A vacuum molding machine, comprising a base member provided with upstanding supports, a plate mounted on the upper ends of the supports, a burner chamber mounted on the plate, a fixed upper die section connected to the plate and having a recessed lower casting space, said die member having an annular flange provided with an annular groove in its lower face and with other grooves extending from the annular groove to the casting space, a melting pot positioned within the burner chamber and having a discharge opening at its lower end which is in communication with the upper portion of the casting space of the upper die section, a valve member controlling said discharge opening, means for heating said burner chamber, a vertically extending cylinder mounted on said base member and provided with a piston member slidably extending therein, a lower movable die section mounted on the upper end of the piston member and having an annular flange provided with an annular groove registering with the annular groove of the upper die section, a sealing ring positioned in one of the annular grooves and adapted to enter

the other annular groove when the die sections are in engagement with each other to form a casting space, means for supplying fluid under pressure to the cylinder, and means for exhausting the air from the casting space between the two die sections preparatory to supplying the molten material to said space.

9. In a vacuum molding machine, the combination, with a frame, of a fixed die member mounted thereon, a die member movably mounted in the frame and movable to a position adjacent the fixed die member to form a casting space therebetween, means for conducting metal to the casting space, means carried by the die members for sealing them together to form an air-tight joint between the same, means for exhausting the air from the casting space, and sprung-pressed stripper rods slidably mounted in the movable die member and automatically operable to remove the cast article from the movable die member when said die member is moved away from the fixed die member.

10. In a vacuum molding machine, the combination, with a frame, a burner chamber mounted thereon, a melting pot disposed within the burner chamber and having a discharge opening at its lower end, and a valve member controlling the discharge opening, of a die member secured to the frame beneath the melting pot and having an opening therein communicating with said discharge opening, a die member vertically movable with respect to the frame and said fixed die to form a casting space between said members, means for sealing the joint between the die members, means for exhausting the air from the casting space of the die members, and stripper rods carried by the movable die member.

In testimony whereof, I affix my signature, in presence of two witnesses.

CONRAD WERRA.
